UNITED STATES PATENT OFFICE.

SOL ADELMAN, OF CHICAGO, ILLINOIS.

COMBINED BOX-HANGER AND GROUND-CLAMP.

No. 910,765.

Specification of Letters Patent.

Patented Jan. 26, 1909.

Application filed May 18, 1908. Serial No. 433,456.

To all whom it may concern:

Be it known that I, SOL ADELMAN, a citizen of the United States of America, and resident of Chicago, Illinois, have invented a certain new and useful Improvement in a Combined Box-Hanger and Ground-Clamp, of which the following is a specification.

My invention relates to improvements in combined box hangers and ground clamps, and has for its object the production of a device by means of which a box may be provided that can be readily attached in place, and one that will provide a ground contact.

A further object is the production of a device that can be easily attached to completed work without tearing away to any great extent the adjacent material, and at the same time furnish a rigid support for the wires passing therethrough.

A further object is the production of a device that can be readily formed from a single sheet of metal without waste and at small cost.

A further object is the production of a device that is of a durable nature, and one that cannot become disarranged from its position.

These and such other objects as may hereinafter appear are attained by my device, embodiments of which are illustrated in the accompanying drawings, in which—

Figure 1 represents a plan view of an outlet box provided with my improved ground clamping device. Fig. 2 is a sectional view on the line 2—2 of Fig. 1, looking in the direction indicated by arrows. Fig. 3 is a perspective view of my ground clamp. Fig. 4 is a perspective view of a modified form of my device. Fig. 5 is a plan view of a blank from which the form illustrated in Fig. 4 is made.

Like numerals of reference indicate like parts in the several figures of the drawing.

Referring by numeral to the accompanying drawings, 6 represents an ordinary outlet box provided with a circumferential flange 7 and provided with partially punched-out portions 8 and a central opening 9, and holes 10 for the insertion of bolts or screws to secure the box in place. The ground clamp proper is formed from a flat sheet of metal 11 shown in Fig. 5, having ears 12 extending preferably at right angles therefrom, and provided with bolt-holes 13 at its ends. The ears 12 are turned at right angles to the body of the plate 11 and the plate turned into a

cylindrical shape as shown in Fig. 4, the upper cylindrical portion 14 being adapted to encircle the pipe running through the opening 9. The extreme ends of the blank 11 are turned outwardly, forming lugs or flanges 15, the bolt-holes 13 registering with each other, through which bolts 16 may be secured.

In the form illustrated in Fig. 3, the clamp is shown as provided with four supporting members or ears at right angles to the cylindrical portion 14. When the device is manufactured in this form, it is simply necessary to use a rectangular blank with extending portions to form flanges 17, the lower portion 70 of the blank being split and the metal turned at right angles, forming the supporting members 12. These supporting legs or ears 12 are provided with bolt-holes 18, by means of which bolts or rivets may be passed therethrough and through the bottom of the box, holding the ground clamp securely in place.

It will be noted, by reference to Fig. 1, that there is ordinarily space left between the flanges 17 to permit the screwing up of the bolt 16, in order to have the cylindrical member grip tightly the pipe which it surrounds, thus forming an intimate ground contact.

Between the adjacent ears 12—12 are preferably provided flanges 19 at right angles 85 to the bottom of the cylindrical portion 14. These flanges in connection with ears provide a continuous flange about the base of the cylinder. In most cases, the openings through which the pipes extend are somewhat larger than the pipes themselves, leaving an open space about the pipe. This serves to cause drafts, and in cases of fire, gives access to the flames between the floor spaces, and the draft will further accelerate 90 the combustion. This circumferential flange completely closes the opening about the pipe, thus removing all danger from the above sources.

Heretofore in the use of outlet boxes, no provision at all has been made for the securing thereof to the pipe passing through the box, but it has been necessary to cut away a considerable amount of plaster surrounding the opening in the case of completed work, 100 and often to insert supporting timbers and cross joists in order to give a foundation for the box. By the use of my device, however, very little, if any, cutting is necessary, and the box can be securely held in place by 105 means of the cylindrical gripping member 14 bolted securely against the pipe.

The device is of very simple construction, and while I have shown it with two and four supporting legs or ears, it is evident that I am not limited to this number, as other forms 5 may be readily devised which will serve the same purpose without departing from the spirit of my invention.

It is deemed important that the ears 12 extend a considerable distance from the end 10 of the cylindrical portion so as to give a firm bearing on the outlet box and that the flanges 19 be in the same plane as said ears and join the same so as to not only serve as means for closing the opening around the pipe but also 15 for affording greater strength at the point of junction of said ears with the cylindrical portion. Furthermore, it is deemed important that the said flanges and ears be in the same horizontal plane so as to be applied upon the 20 one side of the outlet box, thus avoiding the necessity of having to clamp portions upon the side of the box opposite that upon which the cylindrical portion is located.

I claim:

25 1. In a device of the class described, the combination with an outlet box, of a ground clamp, said ground clamp comprising a split cylindrical sleeve having a plurality of sup-

porting ears at right angles thereto and adapted to be rigidly secured to said outlet 30 box, and provided with supplemental flanges extending from said sleeve between said ears and in the same horizontal plane, said ears extending outwardly beyond said flanges to provide a firm extended bearing.

2. In a device of the class described, the combination with an outlet box, of a ground clamp comprising a split cylindrical sleeve having its sides terminating in parallel flanges adapted to be pressed together, and provided with a plurality of supporting ears extending at right angles to said cylinder, adapted to be rigidly secured to said outlet box, and provided with supplemental flanges extending at right angles from said sleeve 40 between said ears and in the same horizontal plane, said ears extending outwardly beyond said flanges to provide a firm extended bearing.

Signed by me at Chicago, Illinois, this 4th 50 day of May, 1908.

SOL ADELMAN.
